UNITED STATES PATENT OFFICE

RUSSELL T. SMITH, OF GREENVILLE, MICHIGAN, ASSIGNOR TO GIBSON REFRIGERATOR COMPANY, OF GREENVILLE, MICHIGAN, A CORPORATION OF MICHIGAN

EVAPORATING UNIT

Application filed February 19, 1931. Serial No. 516,976.

This invention relates to refrigerators and more particularly to evaporator units especially adapted for use with dry or expansion valve systems.

5 Refrigerators of the dry or expansion valve system are provided with evaporators each of which usually consists of copper tubing shaped to form a coil inside which may be disposed the freezing trays. Evaporators so formed are extremely expensive because of the cost of copper and also because of the expense involved in properly shaping the tubes forming the evaporator.

10 In refrigerators of the wet or flooded system however, the evaporators are much more simple and economical, comprising a hollow-walled, tray-surrounding shell, the interior of the hollow wall of the shell being in communication with the compressor unit. Evaporators of this type are generally made of sheet metal, properly corrugated for strengthening purposes, and are much more economical than the continuous copper tube coil evaporator generally used with expansion valve systems.

15 An object of this invention, therefore, is an evaporator for expansion valve systems which is as simple and economical of manufacture as the sheet metal evaporator used with the so-called "wet systems". The evaporator may be formed of sheet metal, and comprises a hollow-walled, tray-surrounding shell having an enlarged portion in which is disposed a coiled copper tube whose inlet is connected to the expansion valve and whose outlet is connected to the suction side of the compressor. The hollow wall is filled with sulphur dioxide which is kept sealed from, but in heat-transferring contact with, the refrigerating medium in the coiled copper tube.

20 A further object is an evaporator comprising a tank, a hollow-walled, sheet metal, tray-surrounding, U-shaped shell whose hollow wall is in communication with the interior of the tank, there being in the latter a coiled copper tube whose inlet and outlet portions are connected to the expansion valve and to the compressor respectively. The hollow wall and the tank are filled with a heat transferring fluid, such as sulphur dioxide,

and the latter is in intimate contact with the coiled copper tube, the latter being provided with fins by means of which heat transfer between the fluid in the tank and the fluid in the copper tube is more readily effected, 55 tho these fluids are completely sealed from each other.

Another object is a dry system refrigerator evaporator unit containing two relatively sealed refrigerating mediums, maintained in 60 heat transferring relation with each other, the primary one of the mediums circulating thru the refrigerator system, that is the compressor, condenser, and expansion valve and the secondary or other medium circulating thru 65 the refrigerating compartment or food cabinet. In an evaporator of this type, the primary medium will absorb heat from the secondary medium, tho sealed therefrom, and the secondary medium will circulate thru the 70 refrigerating compartment, absorbing heat therefrom and later surrendering the heat thus absorbed to the primary medium.

Further, in an evaporator of this type, it 75 is possible to effect economical refrigeration by virtue of the fact that the volume of the secondary medium is rather small and will, of necessity, circulate thru its part of the evaporator, repeatedly, and at great rate. This is especially true if the surface area 80 of the coil disposed in the body of the secondary medium is relatively large, as can be readily seen.

Further, the primary system is completely sealed from the secondary system, and accordingly, lubricating oil for the compressor introduced in the primary system, will be returned, to the compressor, positively, and without its having been lost or dissipated at 85 any point.

Another object is a novel process of refrigeration, one which consists in cooling a primary medium, presenting the latter to a small, sealed body of secondary medium so 90 as to cool the latter, returning the first medium to heat absorbing mechanical devices such as the compressor and condenser, and circulating the secondary medium thru the refrigerating compartment so as to absorb 95 heat therefrom.

Still further objects are novel forms of evaporators in accordance with the principles outlined above.

Still further objects will readily occur to those skilled in the art upon reference to the following description and the accompanying drawings in which

Fig. 1 shows in partial section the evaporator unit of the invention, this figure being a section as if on the line 1—1 of Fig. 2.

Fig. 2 is a rear view of the evaporator.

Referring to the drawings, it will be seen that the evaporator includes a sheet metal tank 10 having a front cap 12 and a rear cap 14. Secured to the tank and supported thereby is a tray-surrounding, U shaped shell 18 which is formed of an inner plate 20 and an outer plate 22. The plates are connected to each other at their edges by welding, soldering, etc. to form a hollow between the plates, the shell thus being hollow-walled, and the tank is provided with suitable openings 26 by means of which communication between the hollow wall of the shell and the interior 25 of the tank is effected.

The interior plate 20 is provided with ribs 28 to form supports for the trays which are to be inserted into the evaporator from the front, and is further provided with a rib 30, forming a stop to prevent insertion of the trays too far into the evaporator.

Further, the outer plate 22 may be corrugated for stiffening purposes, the valleys 36 of the corrugations forming the hollow 35 wall and the ridges 38 engaging the plate 20, if desired, to present surfaces which may be welded to one another, if desired.

Disposed within the tank is a coil of copper tubing having inlet and outlet portions 40—42 which are connected to the expansion valve and to the suction side of the compressor, not shown, the inlet and outlet portions being sealed to the rear cap 14 of the tank 10 at their points of emergence. The coil occupies a large portion of the volume of the tank 10 and is further provided with a number of fins 44 spaced along the tubing more or less evenly. The fluid within the coil, the primary fluid, may be liquid sulphur dioxide. 45 The interior of the tank and the hollow wall of the tray-receiving shell is filled wholly or partly, as desired, with a heat transferring fluid, such as liquid sulphur dioxide, which, as a secondary fluid boils and condenses on the coil and returns by gravity, and circulates thru the tank and shell, absorbing heat from the shell and, therefore, from the trays, and which gives up its heat to the copper coil disposed within the tank. When introducing 50 the secondary fluid into the tank 10 it is preferred to withdraw all the air from the hollow wall shell so that the secondary liquid refrigerant will operate in a partial vacuum.

It will be noted that the construction is in 55 full accord with an objective in the dry sys-

tem, namely, a complete separation of the primary fluid from all other mediums. The tank and the shell form a completely sealed circulating path for the secondary fluid, the in heat transferring contact with the primary 70 fluid, is completely sealed from the latter.

Further, it will be seen that evaporators of the type are made largely of sheet metal, there being no expensive coil of copper tubing shaped to surround the trays.

It will also be noted that the volume of the secondary fluid system is not large, and therefore, "boiling" or rapid circulation and change of condition can be effected readily and at a great rate, this effecting rapid and effective 80 refrigeration.

Now having described the invention and the preferred embodiment thereof, it is to be understood that the said invention is to be limited, not to the specific details herein set 85 forth, but only by the scope of the claim which follows:

What I claim is:—

In combination, a pair of relatively nested, U shaped, sheet metal plates secured and 90 sealed to each other on their U shaped edges, U shaped formations on at least one of the plates, engaging the other substantially on U lines, to provide U passages between the plates from one pair of upper edges to the other 95 pair, a cylindrical tank between the upper edges and secured and engaged by the plates thereat on opposed elements of the cylinder, the tank having openings connecting the interior thereof, with the U passages, the ends of the tank being closed, and a coiled tube within the tank and having an inlet and an outlet projecting thru the tank, the interior of the tube being sealed from the interior of the tank and the space between the plates.

In testimony whereof, I sign this specification.

RUSSELL T. SMITH.
